UNITED STATES PATENT OFFICE

153,810

DESIGN FOR A COMBINED HAIRPIN
RECEPTACLE AND OPENER

John Joseph Koslap, Garfield, N. J.

Application April 9, 1947, Serial No. 138,263

Term of patent 7 years

(Cl. D86—10)

To all whom it may concern:

Be it known that I, John Joseph Koslap, a citizen of the United States, residing at Garfield, in the county of Bergen and State of New Jersey, have invented a new, original, and ornamental Design for a Combined Hairpin Receptacle and Opener, of which the following is a specification, reference being had to the accompanying drawing, forming part thereof.

Figure 1 is a perspective view of a combined hairpin receptacle and opener, showing my new design, and

Figure 2 is a perspective view on a reduced scale similar to that shown in Figure 1, but showing the cover removed from the receptacle.

I claim:

The ornamental design for a combined hairpin receptacle and opener, as shown.

JOHN JOSEPH KOSLAP.
